(57) **CLAIM**

The ornamental design for an electrical control device, as shown and described.

DESCRIPTION

The electrical control device mounts to an electrical box and is surrounded by a decorative faceplate to make an electrical device assembly.

FIG. 1 is a perspective view of the electrical control device according to a decorative embodiment of the invention; FIG. 2 is a front elevation view of the electrical control device shown in FIG. 1;

FIG. 3 is a top plan view of the electrical control device shown in FIG. 2;

FIG. 4 is a bottom plan view of the electrical control device shown in FIG. 2;

FIG. 5 is a left side elevation view of the electrical control device shown in FIG. 2;

FIG. 6 is a right side elevation view of the electrical control device shown in FIG. 2;

FIG. 7 is a perspective view of another aspect of the electrical control device according to a decorative embodiment of the invention;

FIG. 8 is a perspective view of the electrical control device according to an alternative decorative aspect of the invention;

FIG. 9 a front elevation view of the electrical control device shown in FIG. 8;

FIG. 10 is a a is a left side elevation view of the electrical control device shown in FIG. 8;

FIG. 11 is a right side elevation view of the electrical control device shown in FIG. 8;

FIG. 12 is a top plan view of the electrical control device shown in FIG. 8; and,

FIG. 13 is a bottom plan view of the electrical control device shown in FIG. 8.

The broken line showing of the environment is for illustrative purpose only and forms no part of the claimed design.
